United States Patent Office

Des. 182,834

Patented May 20, 1958

182,834

COMMODE

John J. Lubberts and Lambert J. Mulder, Grand Rapids, Mich., assignors to Tomlinson of High Point, High Point, N. C., a corporation of North Carolina

Application March 15, 1957, Serial No. 45,272

Term of patent 14 years

(Cl. D33—19)

FIG. 1

FIG. 2

Figure 1 is a front perspective view of the commode embodying our new design; and

Figure 2 is a rear perspective view thereof.

The design is characterized by outwardly curved or convex tamboured doors in relation to and in association with other elements of the unitary design as shown.

We claim:

The ornamental design for a commode, substantially as shown and described.
